UNITED STATES PATENT OFFICE.

MAX J. HUBER, OF ANTIOCH, ILLINOIS.

FENCE-POST.

No. 831,611.

Specification of Letters Patent.

Patented Sept. 25, 1906.

Application filed March 27, 1906. Serial No. 308,311.

To all whom it may concern:

Be it known that I, MAX J. HUBER, a citizen of the United States, residing at Antioch, in the county of Lake and State of Illinois, have invented a certain new and useful Improvement in Fence-Posts, of which the following is a full, clear, concise, and exact description, reference being had to the accompanying drawings, forming a part of this specification.

My invention relates to fence-posts or other posts for supporting wires, chains, ropes, or like articles; and its object contemplates improved construction therefor and improved means for clamping the wires to the post.

The post of my invention is formed of sheet material, preferably sheet-iron, and the form from which the post is formed may be stamped integral, the blank having at one vertical edge teeth extending downwardly with rectangular slots between them and at its other parallel edge having similar teeth extending upwardly. The teeth and a strip along the edges are bent over to form flanges, and the body part of the blank is then rolled into cylindrical form to bring the flanges opposite each other with the bases of the opposed slot in horizontal alinement. The lower part of the post is sunk and secured in the ground, and the wires to be held are slipped into opposed slots, whereupon the flanges are drawn together by bolts or other clamping means, the result being that the wires are securely clamped to the post and held both against longitudinal and other displacement.

My invention will be best understood with reference to the accompanying drawings, in which—

Figure 1 shows the blank stamped from sheet material. Fig. 2 shows the blank rolled to cylindrical form to form the post. Fig. 3 is a view showing the top of the post after the flanges have been clamped together. Fig. 4 is a side view showing the relative arrangement of the teeth to clamp the wires, and Fig. 5 is a perspective view showing the finished post with the wires clamped thereto.

The blank 1, which is stamped from sheet material, has at the left edge the rectangular teeth 2, slanting downwardly and forming the rectangular slots 3. Along the right edge of the blank are the rectangular teeth

4, between which are the slots 5. At the lower part of the post the notches or slots 6 and 7 are cut, while below these slots is the part 8, which eventually enters the ground. The tooth edges are bent over along a line below the base of the teeth to form the flanges 9 and 10, and through the body part of these flanges bolt-holes 11 may be punched at the same time that the blank is formed. The blank thus punched is rolled into cylindrical form, as shown in Figs. 2, 3, and 5; the flanges remaining partly open, as shown in Fig. 2. The lower part of the post up to the slots 6 and 7 is sunk and secured in the ground, whereupon the wires W to be supported are placed in the slots between suitable teeth. The bases of the slots when the post is formed are directly opposite, as shown in Fig. 4, but each wire must be kinked or bent slightly, as shown in Fig. 2, when it is inserted in the corresponding slots; but when the wires W reach the base of the slot they may be straightened, and this is usually done by applying tension to the wires after they have been applied to a number of posts. After the wires are pulled tight the bolts 14 and 12, passing through the bolt-holes, are drawn up and the flanges drawn together a sufficient distance to bring clamping action on the wires. This clamping action results from the fact that the wires, which easily engage in the corresponding groove when the flanges are spread, are more or less confined in the triangular openings 13, formed by the crossing of the corresponding teeth as the flanges are drawn together, these crossing teeth more or less pinching the wires to confine them to lock them against longitudinal movement or escape from the post. By drawing the flanges together a greater or less distance the clamping action on the wires may be made greater or less, depending upon the size of the wire, and the range of wires which may be clamped extends from wires which have a diameter slightly greater than one which would fit in the triangular openings with the flanges drawn tightly together to a wire having a diameter equal to the width of the slots. With the smallest wires the flanges would be completely drawn together into engagement, while with larger wires they would have to remain spread more or less. As shown in Fig. 5, bolts 14 may pass through opposite slots instead of through bolt-holes to assist in

drawing the teeth and flanges together. The slots 6 and 7 allow the flanges to be drawn together after the part below said slots has been firmly secured in the ground, and the upper part of the post after drawing together of the flanges and securing of the wires may also be filled with earth, concrete, or other suitable substance.

I do not wish to be limited to the precise construction and arrangements herein shown, as changes may readily be made without departing from the spirit of the invention.

What I claim as new, and desire to secure by Letters Patent is—

15 1. A post formed of an integral stamping of sheet material bent to form a cylindrical shell, the bases of the stamping being bent to an angle thereto to form opposed flanges when the stamping is bent into form, teeth along

20 the edge of each flange, the teeth on the flanges slanting in opposite directions, whereby by the ends thereof overlap to form compartments for receiving wires to be supported, and clamping means for clamping the flanges

25 together to grip the wires.

2. A post formed of a single piece of sheet metal bent into cylindrical form, a section along the edges of the sheet-metal piece being bent to form opposing flanges, teeth cut along 30 the edge of one of said flanges slanting downwardly, teeth cut along the edge of the other flange extending upwardly whereby the ends of the teeth overlap to lock in place wires passing through the slots adjacent to the overlapping teeth, and bolts passing through the flanges for clamping said flanges securely together to cause the overlapping teeth to grip and clamp the wires.

3. A post formed of a single piece of sheet 40 metal having its edges turned over to form flanges and bent into form to bring the flanges opposite each other but separated a distance, teeth along the edge of one of the flanges slanting downwardly, teeth along the edge of the other flange slanting upwardly, the bases 45 of the slots between the teeth on one flange being opposite to the bases of the slots of the teeth on the other flange, and clamping means for drawing the flanges together to grip and 50 to confine wires previously laid in opposite slots.

4. A post formed of a single rectangular piece of sheet material having flanges along its vertical edges and bent into form to bring 55 the flanges opposite each other but normally separated a distance, teeth along the edge of one of said flanges slanting downwardly, teeth along the edge of the other flange slanting upwardly, the bases of the slots between the teeth on one flange being opposite the bases of the slots of the teeth on the other flange whereby the ends of the teeth adjacent to the opposite slot-bases overlap, and means for drawing the flanges toward each other where- 60 by wires laid in opposite slots when the

flanges were spread are gripped and confined between the corresponding overlapping teeth and the corresponding opposite slot-bases.

5. A post formed of a single rectangular piece of sheet material having flanges along its vertical edges and bent into form to bring the flanges opposite each other but normally separated a distance, teeth along the edge of one of said flanges slanting downwardly, teeth along the edge of the other flange slanting upwardly, the bases of the slots between the teeth on one flange being opposite the bases of the slots of the teeth on the other flange, whereby the ends of the teeth adjacent to the opposite slot-bases overlap, and bolts passing through the flanges for drawing the flanges together whereby wires laid in opposite slots when the flanges were spread are gripped and confined between the corresponding overlapping teeth and the corresponding opposite slot-bases.

6. A post formed of a single rectangular stamping of sheet material having flanges along its vertical edges and bent into form to bring the flanges opposite each other but separated a distance, teeth along the edge of one flange slanting downwardly, teeth along the edge of the other flange slanting upwardly, the bases of the slots between the teeth on the two flanges being opposite, clamping means connected with the flanges for drawing the flanges together whereby the overlapping ends of the teeth form restricted compartments for gripping and clamping wires which normally were easily applied in the slots adjacent to the overlapping teeth.

7. A post formed of a normally flat rectangular piece of sheet material bent into cylindrical form, the lower part of said post being adapted to be sunk in the ground, the edges of the upper part thereof being bent outwardly to form opposed flanges which are normally separated a distance, teeth along the edge of one flange extending in one direction, teeth along the edge of the other flange extending in the other direction, whereby the teeth of one flange overlap those of the other, and clamping means for clamping the flanges together to form restricted compartments for wires previously laid in slots between the teeth, the overlapping teeth clamping the wires in said compartments.

8. A post formed of a normally flat rectangular piece of sheet material bent into cylindrical form, the lower part of said post being adapted to be sunk in the ground, the edges of the upper part thereof being bent outwardly to form opposed flanges which are normally separated a distance, teeth along the edge of one flange extending in one direction, teeth along the edge of the other flange extending in the other direction, whereby the teeth of one flange overlap those of the other, clamping means for clamping the flanges together to form restricted compartments for wires previously laid in slots between the teeth, the overlapping teeth clamping the wires in said compartments.

wires previously laid in slots between the teeth, the overlapping teeth clamping the wires in said compartments, and transverse slots between the upper and lower sections of the posts to allow such clamping together of the flanges without causing clamping action at the lower part of the post.

In witness whereof I hereunto subscribe my name this 24th day of March, A. D. 1906.

MAX J. HUBER.
